ATTACHMENT FOR ELECTRIC AMPLIFIERS

Filed Oct. 20, 1926

FIG. 1.

FIG. 2.

FIG. 3.

INVENTOR

Bowden Washington,

BY
R. S. W.
ATTORNEY

UNITED STATES PATENT OFFICE

BOWDEN WASHINGTON, OF NEW YORK, N. Y., ASSIGNOR OF ONE-HALF TO ROBERT S. ALLYN, OF NEW YORK, N. Y.

ATTACHMENT FOR ELECTRIC AMPLIFIERS

Application filed October 20, 1926. Serial No. 142,978.

The main object of my invention is to provide a simple and inexpensive device which will greatly improve the volume and tone quality of existing talking machines or phonographs. Another object is to produce a simple device which may be readily attached to an existing talking machine and will convert said machine into a so-called electrical phonograph. Another object is to provide means whereby the high quality amplification present in the audio frequency amplifiers of many radio receivers may be applied to reproduction from records to a phonograph making use of the tone arm and tone chamber of said phonograph and of the volume control present in many amplifiers. Another object is to provide an attachment of this character by means of which an ordinary phonograph horn may be also readily used on the loud speaker of a radio receiving set by a shift of one connector or the use of a switch.

As is well known the ordinary mechanical phonograph has no means of providing amplification. In other words, the energy applied to the needle by the wavering groove in the record is the maximum amount of energy present in the device and the sound energy issuing from the tone chamber can be but some fraction of this. For this reason, there must be considerable amplitude of vibration of the diaphragm and as this is the case the natural period of the diaphragm must be well within the range of the frequencies to be reproduced. This being so the response of the diaphragm to this fundamental frequency and to the various harmonics of this frequency will be too high in amplitude, thus causing distortion of the music or voice. If the needle operated structure is given a period somewhat higher than the highest desirable harmonics of the instruments usually recorded, this distortion will not be present, but the device will be extremely insensitive.

If an efficient, well designed and faithful electron tube amplifier be inserted between the pick-up device and the reproducing device, an inefficient but faithful pick-up device may be used and efficiency may be sac-

rificed for faithfulness in the reproducing device as well. This, I believe, to be the main reason for the extremely high quality of reproduction from so-called electrical phonographs.

By means of my invention anyone possessing a phonograph and a high quality audio frequency amplifier, either alone or within a radio receiver, may convert said phonograph into a high grade electrical phonograph within a few minutes and without the use of tools.

Referring to the drawing, Fig. 1 is a vertical section of one embodiment of my invention.

Fig. 2 shows a front view of the embodiment disclosed in Fig. 1 with the cover partially broken away.

Fig. 3 is a diagrammatic view of my invention attached to a phonograph and to an audio frequency amplifier with its auxiliary apparatus.

In Figs. 1 and 2, 10 is the casing for the needle actuated pick-up member. It has at its base the flange 11, this flange having four perforations such as 12 and 13. The cover 14 of the casing 10 may be secured by the screws such as 15 and 16. 17 is the armature which is preferably constructed of hard magnetic material and preferably having a high natural period. This armature 17 is actuated by the needle 18 through the lever 19 and the link 20. The lever 19 is pivoted between the two pivot screws 21 and 22 held in the hangers 23 and 24, which are preferably integral with the cover 14. The coils 25 and 26 are held by the L-shaped pole pieces 27 and 28. The outer ends of these pole pieces are clamped beneath the built up permanent magnet structure 29 as at 30 and 31.

The casing 10 is secured to the back of the casing 32 by screws such as 33 and 34. Between the two casings is inserted a soft rubber disc 35 and under the heads of and around the screws 33 and 34 are inserted soft rubber bushings 36 and 37.

The structure of the stationary magnetic system 38 of the reproducing unit is identical with that described for the pick-up unit, although the number of turns and size of wire

on the bobbins 39 and 40 may differ from the windings of 25 and 26. The cover 41 bears the nipple 42 which may be designed to fit the end of the tone arm of the particular make of talking machine to which the device is to be applied. This cover is secured to the casing 32 by the screws such as 43 and 44 and contains the diaphragm 45 which is held in place by the threaded locking ring 46. The armature 17 may be held in place against the casing 10 by the resilient blocks 47 and 48.

In Fig. 3 is shown my combined pick-up device and reproducer 55 attached to the tone arm 56 of the phonograph 57. The terminals 58 and 59 of the pick-up portion are connected to the in-put of the vacuum tube amplifier 60 which may have the gain or volume control 63. The out-put of this amplifier is connected to the terminals 61 and 62 of the reproducing device. The cathode-heating and anode batteries for the amplifier are shown at 66, 67, 68 and 69.

In operation the armature 17 is moved to and from the poles 27 and 28 by the action of the needle 18 in the groove of the phonograph record. Substantially proportional currents are thus induced in the windings 25 and 26. These currents are led by the leads 58' and 59' to the in-put of the amplifier 60 and the greatly amplified out-put is returned by the lead 61' and 62' to the windings 39 and 40 of the out-put unit.

I prefer to provide some means to prevent direct transmission of mechanical vibration or interference between the in-put and out-put portions of the device, as if this vibration was present to any extent an overall oscillation, "howl", or "squeal" might occur. For this reason I have shown the cushion members 35, 36 and 37. It is preferable that the casings 10 and 32 and the covers 14 and 41 be formed of some light and strong material such as, die-cast aluminum or molded phenolic insulation.

It will be noted that the two elements of my device, the pick-up and the reproducer, may be manufactured and adjusted separately before being assembled into a unit by the screws 33, 33', 34 and 34'.

Reversely, the housing consisting of the pick-up and reproducer chambers may be opened on either side without disturbing the other.

On account of the "cut off" present at high frequencies of the average audio frequency amplifier a marked diminution of needle scratch will be noticeable.

It should be understood that I do not wish to limit my invention to the details disclosed in the drawing nor to a magnetic pick-up device as shown, as there is no reason why a microphonic or condenser type of pick-up device may not be substituted.

I claim:

1. An attachment for a phonograph comprising a housing formed of two parts, one part having means for securing it to the tubular tone arm of said phonograph, a needle operated electro-magnetic current modulator mounted in the other part of said housing a current operated sound producer, means for connecting said current modulator to an electronic amplifier and means for connecting the out-put of said amplifier to said current operated sound producer mounted in the first mentioned part of the housing, and non-interfering means of connecting the parts of said housing. 75

2. As an article of manufacture a phonograph attachment comprising a housing having two enclosing chambers, means for acoustically shielding one from the other, a needle operated electro-magnetic current modulating device in one of said chambers and an electromagnetically operated sound producing device in the other chamber, said latter device having a diaphragm and said chamber having an outlet adjacent thereto adapted to be attached to the tone arm of a phonograph. 90

3. An attachment for the tone arm of a phonograph comprising a housing having two parts, a resilient damping means between said parts, an electro-magnetic pick-up in one part of the housing having a stylus holder, an electro-magnetic sound reproducer in the other part of the housing, a tubular device extending from said latter part of the housing and adapted to be slipped on to the tone arm of the phonograph, and means for connecting a vacuum tube amplifier between said pick-up and said sound reproducer. 95

4. An attachment for a phonograph tone arm comprising two cup-shaped casing members, with their closed bottom walls spaced apart by damping means, means for clamping said members together, electromagnets mounted in said members and secured to the bottom walls thereof, an armature and a projecting stylus for the electromagnet in one casing member, a cover member for holding the armature and stylus in place and a diaphragm and an outlet plate secured to the other casing. 100

5. A phonograph attachment comprising two casings one of which has means for securing it on the tone arm of a phonograph, an electromagnet and a diaphragm mounted in said casing, an electromagnet and an armature mounted in the other casing, a needle stylus carried by the latter casing, resilient damping means mounted between said casings and means for clamping said casings together so that they may be handled as a unit. 120

6. A phonograph construction comprising a movable tone arm, an electro-magnetic reproducer removably carried by said tone arm and movable therewith, and including a hous- 125

ing, an electro-magnetic vibrator mounted in the housing, an electro-magnetic pick-up detachably secured to and supported by said housing, and including a casing and electro-magnetic means within said casing, a stylus cooperatively connected with the electro-magnetic pick-up and means for preventing vibratory interference between said casing and said housing.

5 7. In a phonograph a movable tone arm, an electro-magnetic reproducer detachably secured to the tone arm and movable therewith, and including a housing, an electro-magnetic unit mounted within the housing, an air vibrating diaphragm interposed between said unit and the tone arm chamber, an electro-magnetic pick-up mechanism having a casing mounted co-axially with the housing of the reproducer, means for connecting said casing to said housing, damping means located between said casing, and said housing, and a pick-up stylus carried by said casing.

10 8. In a phonograph a movable tone arm, an electro-magnetic reproducer having a housing provided with a tubular extension secured to and movable with the tone arm, an electro magnetic pick-up including a casing having a flange, damping means between 15 said flange and said reproducer housing, and screws for securing said flange to said housing.
